CHARLES NAUCK, OF GULFPORT, MISSISSIPPI, ASSIGNOR OF TWO-THIRDS TO BAKER C. LAWLER, OF GULFPORT, MISSISSIPPI.

WEIGHING SCOOP.

Application filed October 2, 1923. Serial No. 666,164.

To all whom it may concern:

Be it known that I, CHARLES NAUCK, a citizen of the United States, and resident of Gulfport, in the county of Harrison and State of Mississippi, have invented certain new and useful Improvements in Weighing Scoops, of which the following is a specification.

This invention relates to scoops especially adapted for picking up granular and other matter.

Briefly stated an important object of this invention is to provide a scoop having simple means whereby to weigh the contents of the same so as to overcome the necessity of pouring the contents of the scoop into a separate scale.

A further object is to provide a combined scoop and scale which is simple to use, durable in construction and cheap to manufacture.

Other objects and advantages will be apparent during the course of the following description.

In the accompanying drawing forming a part of this application in which like numerals are employed to designate like parts throughout the same,

Figure 1 is a side elevation of the improved scoop and scale, the handle being shown in section to illustrate the scale.

Figure 2 is a longitudinal sectional view through the handle, the lever of the scale being shown in the position it occupies when the scoop is laden with granular or other matter.

Figure 3 is a fragmentary plan view illustrating the handle and a portion of the scoop.

Figure 4 is a detail transverse sectional view taken on line 4—4 of Figure 1.

Figure 5 is a perspective illustrating an indicating arm or lever embodied in the invention.

In the drawing wherein for the purpose of illustration is shown a preferred embodiment of the invention the numeral 5 designates a scoop adapted for picking up and carrying any granular or other matter and as illustrated in Figure 1 the scoop which is carried longitudinally has its rear end portion connected to the flanges 6 of an approximately L-shaped depending extension 7 on the forward end of a main lever 8. The ap-

proximately L-shaped depending extension 7 is secured to the rear end of the scoop by the flanges 6 and by fastening devices 9 which extend through the top of the scoop. The depending L-shaped extension 7 terminates in a return bend which constitutes a bumper 10 adapted to be engaged with the under side of a hollow handle 11 so as to hold the scoop 11 against extensive movement with relation to the handle when the scoop is being moved through a body of material for the purpose of loading the scoop.

The lever 8 is received in the handle 11 and is held in position by means of a combined attaching and tensioning leaf spring 14, the said leaf spring being of U-shaped formation and having a bight portion 15 secured flatly in engagement with the rear end of the handle 11 by means of fastening devices 16. It will be seen that the combined attaching and tensioning leaf spring is provided with a short branch 16 secured to the rear portion of the lever 8 by fastening devices 17 and with a long branch curved longitudinally and flatly engaged with the lower edge of the lever 8 so as to normally hold the lever in the position illustrated in Figure 1.

A thumb screw 18 is threaded through the bottom of the handle 11 and is engaged with the long branch of the U-shaped spring 18 so as to tension the same. By this means the scales may be adjusted.

The forward portion of the handle 8 is enlarged considerably and encloses the major portion of a main indicating lever 20, the lower portion of which is provided with a pivot pin 21 extended through the handle and connected to opposite sides of the same as illustrated in Figure 4.

As illustrated in Figure 5 the lever 21 is provided at its lower end with a lateral branch 23 having a slot 24 extended longitudinally thereof and adapted to receive an actuating pin 26, said actuating pin being extended through the forward portion of the lever 8. It will be seen with reference to Figure 4 that the forward portion of the lever 8 is considerably enlarged and is provided with a slot 27 extended out through the upper and lower edges thereof and receiving the lever 20 so as to hold the lever against lateral movement. However, the slot is of ample length to allow the lever 20

to partake of a free pivotal movement on the pin 26 when the lever 8 is moved either up or down.

5 The upper portion of the lever 20 is provided with a pointer 30 which plays over the curved portion of the handle 11 and cooperates with the calibrations 32 in indicating the weight of the contents of the scoop.

10 In operation the operator grasps the handle 11 and introduces the scoop 5 into the material to be weighed and the curved terminal portion 10 of the L-shaped attaching extension 7 will contact with the bottom of the hollow handle 11 and thereby limit the 15 movement of the scoop with relation to the handle.

15 One side of the handle 11 is provided with a weighted indicator 39 pivotally supported by a pivot pin 40 and the said indicator 20 cooperates with one or more calibrations on the handle 11 to indicate when the handle is held level or horizontal. When the handle 11 has been adjusted in a horizontal position while in the hands of the operator 25 the indicating lever 20 and more particularly the pointer 30 thereon will cooperate with the calibrations 30 to indicate the weight of the contents of the scoop.

30 Attention is especially directed to the fact 30 that during the filling of the scoop the forward end of the hollow handle 11 is entirely closed by the lever 8 and the adjacent portion of the depending extension 7 so that no granular or other matter can accidentally 35 enter the handle. Furthermore, it will be seen that all the major parts of the scale are enclosed within the handle and are protected thereby so that the device will stand rough usage.

40 It is to be understood that the form of the invention herewith shown and described is to be taken as a preferred example of the same and that such minor changes in arrangement and construction of parts may 45 be made as will remain within the spirit of the invention and the scope of what is claimed.

Having thus described the invention, what is claimed is:—

50 1. The combination with a hollow handle open at its forward end, of a lever swingable in the handle having a spring in connection therewith controlling its movement and having its forward end provided with a depending extension at the forward end of the handle, a scoop connected to said extension, and an indicating member pivoted within said handle, said indicating member being provided with a slot, and a pin carried by said first named lever and movable in said slot against the walls thereof whereby to swing said indicating member by movement of the said lever.

55 2. The combination with a hollow handle open at its forward end, of a lever received

in said handle and having its forward end provided with a depending approximately L-shaped extension, a scoop connected to said extension, an indicating lever pivoted to said handle, said indicating lever being 70 provided with a transverse branch having a longitudinal slot, a pin carried by said first named lever and received in said slot whereby to actuate said indicating lever, and a combined attaching and tensioning 75 leaf spring secured in said handle and having a branch rigidly secured to said first named lever and having a second branch flatly engaged with the lever and normally holding the same in a set position. 80

3. The combination with a hollow handle open at its forward end, of a lever received in said handle and having its forward end provided with a depending approximately L-shaped extension, a scoop connected to 85 said extension, an indicating lever pivoted to said handle, said indicating lever being provided with a transverse branch having a longitudinal slot, a pin carried by said first named lever and received in said slot 90 whereby to actuate said indicating lever, a combined attaching and tensioning leaf spring secured in said handle and having a branch rigidly secured to said first named lever and having a second branch flatly engaged with the lever and normally holding the same in a set position, the forward portion of said main lever being provided with a slot extending out through the upper and lower edges thereof and receiving said indicating lever whereby to hold the indicating lever against excessive lateral movement. 95

4. The combination with a hollow handle open at its forward end, of a lever received in said handle and having its forward end 100 provided with a depending approximately L-shaped extension, a scoop connected to said extension, an indicating lever pivoted to said handle, said indicating lever being provided with a transverse branch having 105 a longitudinal slot, a pin carried by said first named lever and received in said slot, whereby to actuate said indicating lever, a combined attaching and tensioning leaf spring secured in said handle and having 110 a branch rigidly secured to said first named lever and having a second branch flatly engaged with the lever and normally holding the same in a set position, the forward portion of said main lever being provided with a slot extending out through the upper and lower edges thereof and receiving said indicating lever whereby to hold the indicating lever against excessive lateral movement, 115 said depending extension and said first named lever constituting a means for normally closing the forward end of said handle and said extension being provided with a return bend constituting a bumper. 120

CHARLES NAUCK.
